Des. 210,377
Patented Mar. 5, 1968

210,377

ELECTRICAL DISTRIBUTION UNIT

Rodrigo Lopez-Fabrega, Norwalk, and Kenneth Van Dyck, Southport, Conn., assignors to Harvey Hubbell, Incorporated, Bridgeport, Conn., a corporation of Connecticut

Filed June 29, 1966, Ser. No. 2,850

Term of patent 14 years

(Cl. D26—5)

Fig. 1.

Fig. 2.

Fig. 3.

Fig. 4.

Fig. 5.

Fig. 6.

FIG. 1 is a perspective view of an electrical distribution unit incorporating our new design and showing the front, top and one side thereof;

FIG. 2 is a perspective view showing the front, bottom and other side thereof;

FIG. 3 is a top plan view thereof;

FIG. 4 is a front elevational view thereof;

FIG. 5 is a side elevational view thereof showing the side shown in FIG. 1, and

FIG. 6 is a bottom plan view thereof.

The dominant features of our new design are shown in solid lines in the drawings.

We claim:

The ornamental design for an electrical distribution unit, substantially as shown and described.
